UNITED STATES PATENT OFFICE.

FRANK B. KENNEY AND JOHN W. SIDEBOTTOM, OF LOWELL, MASSACHUSETTS, AS-SIGNORS TO T. C. ENTWISTLE COMPANY, OF LOWELL, MASSACHUSETTS, A CORPORATION OF MASSACHUSETTS.

PNEUMATIC LINT CLEARER FOR WARPING MACHINES AND THE LIKE.

Application filed March 12, 1923. Serial No. 624,368.

To all whom it may concern:

Be it known that we, FRANK B. KENNEY and JOHN W. SIDEBOTTOM, citizens of the United States, residing at Lowell, in the 5 county of Middlesex, State of Massachusetts, have invented a certain new and useful Improvement in Pneumatic Lint Clearers for Warping Machines and the like, of which the following is a specification, reference being had therein to the accompanying drawings.

The invention is an improvement in pneumatic lint-clearing or removing devices of the class of that described and claimed in 15 United States Letters Patent No. 1,339,182 granted May 4, 1920, upon application of James E. Farrell.

As in the case of the device of the Letters Patent just mentioned, a device embodying the features of the present invention is applicable to warping machines, looms, and other machines in which a series of yarns or threads travel onward side by side; and the improved device is adapted 25 to serve the same general purposes as such formed device, namely that of clearing lint from the yarns or threads, combs, guides, drop-wires, and the like, in the said machines; that of preventing lint from becoming attached to the yarns or threads so as to 30 make "slugs" or bunches in the cloth into which the yarns or threads are woven; and that of preventing the stop motion mechanisms of the machines from being rendered 35 inoperative through clogging by accumulated lint.

The invention provides a lint-clearer device of simpler and less expensive character and construction than the device of the 40 said Letters Patent. The latter includes a fan blower which is made to travel back and forth across the machine with which it is combined, by means of a rotating traverse screw having an endless or right and left 45 screw thread, such travel being designed to cause the blast or current of air from the blower to act uniformly at all points in the width of the machine. The fan blower of said Letters Patent also is mounted at an 50 inclination in connection with its carriage, and is intermittently turned step by step around a vertical axis by means of pawl and ratchet devices so as to send the blast or current in different directions successively,

and thereby reach all portions of the yarns 55 or threads and machine, front and rear, in turn.

In the case of a pneumatic lint-clearer embodying the present invention, the blower that is employed occupies a definite location 60 in the machine to which it is applied, and has combined therewith moving means therefore by which the blower is swung transversely of the machine so as to cause the blast or current of air to play back and 65 forth across the width of the series of yarns or threads; and by which, also, the blower is vibrated in a direction at right angles to such swinging movement so as to cause the blast or current to play forward and rear- 70 ward in the direction of the length of the yarns or threads.

An illustrative embodiment of the invention is shown in the accompanying drawings, in which latter,—

Fig. 1 is a front view of a portion of the width of a warping machine having the 75 said embodiment applied thereto.

Fig. 2 is a side view of the machine and lint-clearer device of Fig. 1, certain parts 80 having been removed on line 2, 2, of Fig. 1.

Fig. 3 is a view in vertical section in the plane of dotted line 3, 3, of Fig. 1, showing a series of yarns or threads, the stop motion devices, etc.

Fig. 4 is a partly sectional view on a larger scale, showing the blower and a part of the means for oscillating the same.

Having reference to the drawings,— The drawings represent a typical warping 90 machine and the arrangement, etc., of the lint-clearer device in connection therewith.

In Figs. 2 and 3, yarns or threads 1 are represented as extending through the back comb 2 as if coming from a warper creel 95 (not shown). The said yarns or threads pass from the back comb 2 over a measuring roll 3, under the movable falling rod 4, Fig. 3, over the supporting roll 5, through the front comb 6, and over the front supporting roll 7, from which latter they pass downward to the warper beam 8, whereon they are wound by the action of the machine. Drop-wires 9, 9, 9, are represented as hung 100 in the usual manner upon the yarns or threads at points between the rear supporting roll 5 and the front comb 6. At 11 is 105 the blower of the illustrated embodiment of

the invention. It is shown applied and arranged to operate to blow away lint from the yarns or threads during their passage from rear to front at the top of the machine, and to keep the back and front combs, drop-wires, and other parts adjacent the drop-wires, in addition to the yarns themselves, free and clear from lint.

In this embodiment of the invention the blower is mounted in a position above the yarns or threads, etc., upon a support 10 in the form of a shaft extending across the width of the machine, above the top of the latter, and mounted in bearings 100 in the upper ends of stands 111 upon the tops of the side-frames of the warping machine. One of such stands is partly broken away in Fig. 2. In this instance the blower is located at midwidth of the series of yarns or threads, which is an effective position for enabling the blower to keep the yarns or threads and the desired machine parts clear of lint, and is an electric fan 11, which is preferred, although the invention is not necessarily restricted in all instances to the use of a fan blower.

To provide for swinging movements of the said fan 11 transversely of the machine, it is mounted between the depending arms of a bail or yoke 12, that hangs down from the supporting shaft 10, the fan-casing being furnished with journals 13, 13, working in bearings in connection with the said arms. The bail or yoke occupies a vertical plane corresponding in general direction with the length of the yarns or threads, so that the fan swings on the said journals around a horizontal axis in a vertical plane extending fore-and-aft of the warper at, or substantially at, right angles with the said length.

To provide for the convenient connection of the yoke with the supporting shaft 10, a collar 26 is placed upon the said shaft and fixed thereto at the desired point in the width of the machine by means of a clamping screw 27, the said collar being furnished with a downwardly-extending stud or pin 260. The bail or yoke is provided with a hub 40, which fits upon the said stud or pin, and a clamping screw 41 applied to the said hub serves to hold the bail or yoke in place upon the stud or pin, with capacity for adjustment up and down to vary the height of the fan above the yarns or threads, etc., and also with capacity for angular adjustment around the stud or pin in case it should be desired to vary the angle which the plane in which the fan swings makes relative to the length of the yarns or threads. If desired, the fan may be shifted along the shaft 10, to locate it at any required point intermediate the sides of the machine.

In this instance, well-known devices, actuated by the rotation of the fan itself, are shown for producing the transverse swing-

ing movements of the fan on its journals automatically. Such devices comprise a jack-shaft 14, Figs. 2, 3 and 4, gear-driven by the main fan-shaft, extending outwardly from the fan-casing, and having fixed on its outer end the disk or plate 15, and a link 16 coupled at one of its ends to a crank-pin 17, Fig. 4, borne by the disk 15, and at its other end to a pivot pin 18, Fig. 1, fixed at the outer extremity of a suitable member which is in turn fixed upon the bail or yoke 12, such as an arm 19 having the attaching portion thereof fixed in a hole provided for it in one arm of the bail or yoke. When the fan rotates the jack-shaft 14 rotates also, moving the crank-pin 17 in a circular path with respect to said jack-shaft. Inasmuch as the link 16 is pivoted at one end to a member fixed with respect to the bail 12 and cannot move in the direction of its length, the circular travel of the crank-pin 17 to which the other end of said link is attached serves to swing the fan back and forth upon its journals 13, 13.

For the purpose of vibrating the blower in a direction at right angles to the transverse swinging movement just described, we combine with means for producing the above-described transverse oscillation of the fan-blower, means for producing a swinging movement fore-and-aft of the machine; that is to say, in the direction of the length of the yarns or threads. To this end, in the present instance, we fix upon the supporting shaft 10 by a clamping screw 29 a crank-arm 28 which is operatively combined by means of a link 30 with the free end of a lever 31 that is pivoted to the machine-frame at 32, the said lever being actuated through the engagement of a cam-follower 33 midway of its length with a cam-path 34 formed in one side-face of a spur-gear wheel 35 rotating on a stud 36 secured to the machine-frame. This spur-gear wheel 35 is driven through engagement with a spur-gear 37 fixed upon the shaft 38 of the beam driving drum 39.

By causing the blast or current to play forward and rearward in the direction of the length of the yarns or threads, in addition to playing across transversely of the yarns or threads, the lint-clearing blast or current of air from the blower is completely distributed.

Thus we secure a composite movement of the fan, the oscillation thereof about the axis of the journals 13 and the swinging movement about the axis of the shaft 10 being at right angles to each other.

The fan is shown provided with a guard 21 of usual character about its blades. In practice, suitable lead-wires are connected with the fan. In the drawings, these lead-wires merely are indicated diagrammatically at x, y , to enable their general course to be traced. A suitable switch is provided

- for controlling the electric current which drives the fan. In this instance, such switch is indicated at 22, Fig. 3, located at the bottom of one end of the machine. The plunger 220 thereof is arranged to be depressed by a finger 23 upon the pedal rockshaft 24 to close the switch and let the current flow only when the warping machine is running on high speed. In this manner just described the blower is automatically set in action as soon as the warping machine is put on high speed and is caused to oscillate to direct its blast back and forth across the width of the machine.
- 15 We claim as our invention,—
1. In a warping machine, or the like, a lint-clearer comprising a blower, means for swinging the blower to cause the current of air therefrom to change direction back and forth transversely across the width of the machine, and means actuated from the driving mechanism of the machine for swinging the blower fore-and-aft of the machine.
  2. In a warping machine, or the like, a lint-clearer comprising a blower pivoted in its mounting for swinging movement transversely of the machine, means for imparting such swinging movement, and means for swinging the blower fore-and-aft of the machine comprising an actuating cam, and a rocking support for the blower mounting actuated by said cam.
  3. In a warping machine, or the like, in combination, a supporting shaft, a blower mounted upon said shaft, means for swinging the blower to cause its blast to sweep fore-and-aft of the machine comprising an arm upon said shaft, a cam, a cam-actuated member, and a link connecting said member and the said arm, and means for swinging the blower transversely of the machine.
  4. In a warping machine, or the like, in combination, a supporting shaft, a blower mounted upon said shaft, and means for swinging the blower to cause its blast to sweep the parts below, said means comprising an arm upon said shaft, a cam, a cam-actuated member, and a link connecting said member and the said arm.
  5. In a warping machine, or the like, a lint-clearer comprising a blower located at a fixed point in the width of the machine, and means for oscillating the blower in the direction of the length of the yarns or threads traveling through the machine.
  6. In a warping machine, or the like, a lint-clearer comprising a blower located at a fixed point in the width of the machine, means for swinging such blower to cause the current or blast of air therefrom to sweep transversely of the series of yarns or threads in the machine, and means for oscillating the blower in the direction of the length of the said yarns or threads.

FRANK B. KENNEY.
JOHN W. SIDEBOTTOM.
